UNITED STATES PATENT OFFICE

JOSEPH H. POWERS, OF CODY, WYOMING

DESIGN FOR AN AUTOMOBILE SIGNAL HOUSING

Application filed August 10, 1929. Serial No. 32,373. Term of patent 7 years.

To all whom it may concern:

Be it known that I, JOSEPH H. POWERS, a citizen of the United States, residing at Cody, in the county of Park and State of Wyoming, have invented a new, original, and ornamental Design for Automobile Signal Housings, of which the following is a specification, reference being had to the accompanying drawing, forming part thereof.

The signal housing shown and claimed is to be attached to the left side of an automobile near the front end thereof for signaling an intention to turn to the left.

In the drawing:

Fig. 1 is a front elevation of the automobile signal housing showing my new design.

Fig. 2 is an end elevation thereof, and

Fig. 3 is a rear elevation of the automobile signal housing.

I claim:

The ornamental design for an automobile signal housing, as shown and described.

In testimony whereof I affix my signature.

JOSEPH H. POWERS.
